10

This invention relates to magnetic information retaining devices and to a novel magnetic medium for use therewith. More particularly, the present invention relates to a device for storing magnetic informational domains within elongated magnetic media comprising nickel, iron, zirconium, and optionally niobium.

Electrical information handling circuits employing individual memory elements of a material having substantially nonlinear characteristics whereby the memory elements are enabled to remain in either of two stable states are well known. Circuits of this general type are extensively represented in the art in numerous forms and may advantageously employ memory elements of a ferromagnetic material.

One well known information handling circuit in which ferromagnetic memory elements may be employed is a shift register circuit. In such a circuit, binary information may be introduced at one point and temporarily stored or delayed by shifting it along successive information addresses to another point in the circuit by utilizing the principle of establishing and shifting magnetic domains of selected polarities through a magnetic medium.

Memory structures of this type are generally divided into a plurality of individually polarizable discrete segments having an interaction therebetween with a predetermined number of such segments making up each of the information addresses. Initially, the segments of each of the addresses are polarized in the same direction. An information bit such as a binary "1," for example, is introduced into a first address of the memory structure by reversing all the segments of that address to the opposite direction, thereby establishing a pair of domain walls that can be moved continually along the magnetic medium which comprises the sum of the discrete segments.

Movement of the domain walls and shifting of the information bit along the memory element is accomplished by simultaneously restoring the first segment of the instant address to its initial polarization and reversing the polarity of the next segment following the last segment of the instant address. A new alignment of segments and propagation of the domain walls results, and the information address has in this manner been shifted one segment portion. As an information bit is shifted along the memory element in successive phases of operation, the bit occupies a succession of adjacent bit addresses. When the last address portion of the memory element is reached, the information bit may be read out by detecting a flux change in the final segment due to the presence of the domain walls in that address. If a binary "1" for example, has been shifted to that portion, each of the segments in the last address will be reversed relative to the initial polarization, and this reversal of polarization may be detected as a read out signal by means well known in the art.

In general, shifting of magnetic domain walls separating two regions of opposing magnetization in a magnetic medium may be accomplished by applying a control magnetic field, H , parallel to the magnetization of that region which it is desired to expand by applying current pulses

2

to a suitable propagation coil. The axial velocity of the resultant domain wall is proportional to $(H - H_c)$ where H_c is the critical field below which propagation of the wall will not occur, the value of H being less than H_n , the axial magnetic field necessary to nucleate a reversed magnetization section in the magnetic medium. Devices of the described type will operate with any magnetic medium evidencing a ratio of H_n/H_c . Unfortunately, few of the known magnetic media evidence H_n/H_c ratios greater than one unless maintained under tension, generally within 50 percent of their yield point. Accordingly, device fabrication is a costly and complicated procedure for which workers in the art have long sought a remedy.

In accordance with the present invention there is described a novel magnetic medium manifesting a ratio of H_n/H_c substantially greater than one without the application of tension, such medium being of particular interest for use in shift registers of the type described herein. The described medium comprises from 0.1 to 3.0 percent, by weight, zirconium, 0.0 to 5.0 percent, by weight, niobium, 72.0-84.0 percent, by weight, nickel, remainder iron, wherein the ratio of nickel to iron is within the approximate range of from 3:1 through 7:1. A reentrant hysteresis loop can be developed in the material, and the materials herein are otherwise such as to suggest their use in memory elements.

The invention has been described largely in terms of a magnetic shift register utilizing the described composition. However, it will be understood that the magnetic shift register alluded to herein is intended merely to be exemplary of a significant use of the novel composition. It is further to be understood that the described composition may be used in the formation of magnetic memory elements based on principles of operation different than those of the noted shift register, and it will be appreciated that any magnetic device or structure which requires magnetic elements displaying a reentrant hysteresis characteristics may be fabricated with the described composition.

The invention will be more readily understood by reference to the following detailed description taken in conjunction with the accompanying drawing, wherein:

The figure depicts an exemplary shift register utilizing a magnetic medium of the present invention.

With reference now more particularly to the figure, there is shown an exemplary magnetic shift register utilizing the composition described herein as a magnetic medium. Shown in the figure is a nonconductive mounting cylinder 11 having disposed therein two overlapping groups of evenly spaced conductors parallel to the longitudinal axis of cylinder 11, such forming the polyphase conductor array. The lower or underlying portion of the conductor array comprises a plurality of flat rectangular members, for example, 12, 13, and 14, which are partially covered by the upper layer comprising rectangular shaped members 15, 16, and 17. As shown in the figure, the conductors are curved to conform to the circular configuration of the structural cylinder 11.

Immediately adjacent to the conductor array, there is shown a magnetic wire 18 wound in a helix about cylinder 11 and comprising the composition described herein.

In the system being described utilizing magnetic wire 18 for each shift register channel, the recording is performed by establishing a pair of domain walls of like polarity by a write coil 19 that can be moved along continuously from one bit address to another, and sensing is performed by detecting a flux change in the final segment of the wire due to the presence of the domain walls by read coil 20.

In the driving system described herein utilizing a plu-

rality of polyphase conductors to provide a continuous circular driving field, conductors 13 and 14 and conductors 16 and 17 are connected together through leads 21 and 22 respectively at one end. At the other end, conductors 13 and 16 are shown connected through leads 23 and 24 respectively to a driving circuit 25, and conductors 14 and 17 are connected to ground. The described system also employs a clock 26 to provide timing through lead 27 to the driving circuit and through lead 28 to the write circuit 29, which is connected to write coil 19 by lead 30, the other end of coil 19 being connected to ground. Information is applied to the system from a source of information 32 through lead 33 to the write circuit 29, the source of information being timed by clock 26. The read circuit 34 is connected to lead coil 20 and lead 35, the other end of coil 20 being connected to ground. Signals representing interrogated information are applied by lead 36 to the source of information 32, for example.

A typical procedure for the preparation of the composition of the present invention follows:

The first step involves preparing a melt containing iron, nickel, zirconium, and optionally niobium in the desired proportions by introducing the high purity virgin metals into a high frequency induction furnace and heating in a helium atmosphere until the melting point is reached. Next, the molten mixture is poured into a water cooled copper cylindrical mold, typically 0.5 inch in internal diameter. After cooling, the cast rod is hot swaged at 1,000–1,100° C., typically to 0.250 inch diameter and surface oxides are removed by grit blasting. Then, the resultant rod is cold swaged to 0.060 inch diameter and annealed to 1,000° C. in a helium atmosphere. Following, the material is cold drawn to the desired diameter. The resultant metal wire is now ready for winding about the mounting cylinder 11 described in the figure or for fabrication into a memory storage device.

In the fabrication of compositions destined for use in devices of the described type, it is desirable that the compositions be produced by a series of processing steps terminating in cold reduction of at least 90 percent in area, as for example, by drawing. However, such processing is not required for all uses contemplated for the described compositions.

As noted above, compositions containing from 72.0 to 84.0 percent nickel, by weight, of the total composition, wherein the ratio of nickel to iron is within the approximate range of 3:1 to 7:1 are of interest in the present application. The percentage of zirconium and/or niobium to be added to the nickel-iron mixture is controlled by the nature of the characteristics desired, that is, coercive force and squareness ratio evidenced by the resultant materials as well as the H_n/H_c ratio. For the purposes described herein, from 0.1 to 3.0 percent, by weight, zirconium, and from 0.0 to 5.0 percent, by weight, niobium, based on the weight of the total composition may be employed, a general preference being found for a range of compositions in which zirconium is present in an amount within the range of 0.3 to 0.7 percent, by weight. Variations below or above the noted ranges adversely affects the H_n/H_c ratio.

The following examples are given by way of illustration and in limitation unless otherwise mentioned in the appended claims.

EXAMPLE 1

A melt was prepared containing 82.8 parts nickel, 17.2 parts iron, and 1.0 part zirconium, by introducing the high purity virgin metals into a high frequency induction furnace and heating in a helium atmosphere until the melting point was reached. Next, the molten mixture was poured into a water cooled copper cylindrical mold 0.5 inch in internal diameter. After cooling, the cast rod was hot swaged to 0.250 inch diameter at 1,000° C. and surface oxides removed therefrom by grit blasting. Thereafter, the resultant rod was cold swaged to 0.060 inch diameter and annealed at 1,000° C. in a helium atmosphere. Following, the material was cold drawn to 1.3 mils. As drawn, the material evidenced a wall propagation field of approximately 5 oersteds. Further annealing of the material at 900° C. resulted in a diminution of the wall propagation field from 5 to 3 oersteds with the retention of a reentrant hysteresis characteristic.

EXAMPLE 2

The procedure of Example 1 was repeated employing a melt containing 79.4 parts nickel, 17.1 parts iron, 0.5 part zirconium, and 3.0 parts niobium. The resultant composition as drawn to 0.8 mil evidenced a wall propagation field of approximately 2.8 oersteds and a reentrant hysteresis characteristic. Further annealing at 700° C. resulted in a lessening of the wall propagation field to 1.6 oersteds with the retention of a reentrant hysteresis characteristic.

What is claimed is:

1. A composition of matter consisting essentially of 0.1–3.0 percent, by weight, zirconium, up to 5.0 percent, by weight, niobium, 72.0–84.0 percent, by weight, nickel, remainder iron, wherein the ratio of nickel to iron is within the approximate range of 3:1 to 7:1.
2. A magnetic memory element comprising a magnetic conductor consisting essentially of 0.1–3 percent, by weight, zirconium, up to 5.0 percent, by weight, niobium, 72.0–84.0 percent by weight, nickel, remainder iron, wherein the ratio of nickel to iron is within the approximate range of 3:1 to 7:1.
3. A magnetic shift register storage device comprising an elongated magnetic element, means for establishing magnetic domains in said magnetic element and means for shifting said magnetic domain along said magnetic element, said magnetic element consisting essentially of 0.1–3.0 percent, by weight, zirconium, up to 5.0 percent, by weight, niobium, 72.0–84.0 percent, by weight, nickel, remainder iron, wherein the ratio of nickel to iron is within the approximate range of 3:1 to 7:1.
